BOTTLE CARRIER

Julius Nemetz, Rockford, Ill.

Application January 22, 1941, Serial No. 375,408

3 Claims.

(Cl. 224—48)

This invention relates to an improved device for carrying and holding a plurality of containers such as narrow-necked bottles used for soft drinks and the like.

It is a common practice for a consumer to purchase refreshments drinks, as pop, in quantity lots such as three or six bottles at a time. Because of the difficulty in handling and carrying a quantity of loose bottles, carriers are often provided for the convenience of the purchaser. Normally the procedure is for the purchaser to pay a deposit on the bottles upon receiving them from the grocer or other retailer and apply for a refund upon their return. In any event, the empty bottles are usually returned, and it is as important to provide a carrier that will be serviceable for all handling incident to the use and return of bottles as it is to the purchase thereof. In the past these carriers have commonly been made of a material such as cardboard that is subject to damage or destruction, such as through absorption of moisture or tearing through handling, either of which is apt to terminate the useful life of the carrier prior to the time the empty bottles are returned, or render it unattractive. If a carrier avoided these difficulties and were suitable for continued use after its return, it obviously would be of much greater benefit to the consumer and seller, so far as the factors of serviceability, appearance and replacement cost are concerned. It is, therefore, the principal object of my invention to provide an improved bottle carrier of a relatively inexpensive and simplified construction that will withstand repeated usage and handling and will retain its neat appearance.

Another object of my invention is to provide a bottle carrier for a plurality of bottles that holds the bottles firmly in an inter-nested relation to reduce breakage and noise incident to their bumping together.

A further object of my invention is to provide a bottle carrier of a serviceable and durable type that may be collapsed for stacking in a limited space while in storage or shipment.

It is also an object of my invention to provide a carrier which when filled with its complement of bottles occupies a space substantially equivalent to that occupied by the bottles themselves, for storage, display and shipment in a minimum of space, and can be stacked with like carriers, one upon the other, for transportation or display.

Other objects of my invention such as its adaptability for display purposes will appear from the following description and figures, wherein—

Figure 1 is an end elevation of that embodiment of my invention adapted for carrying a double row of bottles;

Fig. 2 is a side view of the device;

Fig. 3 is a perspective view of the invention in a collapsed position;

Fig. 4 is a view on the line 4—4 of Fig. 3 illustrating how a plurality of carriers may be stacked one upon the other;

Fig. 5 is an end elevation of the modification of my invention suitable for carrying a single row of bottles;

Fig. 6 is a top elevation on the line 6—6 of Fig. 5, and

Fig. 7 is a perspective view of vertically stacked bottle cases, one of which is sectioned to show loaded carriers therein.

Referring to the embodiment of my invention shown in Figs. 1 to 4, which especially adapted for use with smaller beverage bottles such, for example, as the standard six, eight or twelve ounce bottles, the bottom is formed of three wire members 7, 8 and 9, the first of which, 7, defines the configuration of the bottom and consists of a single wire member whose ends are secured together by a method such as solder. The wire member 7 is generally oblong in shape and has end portions 11 and 12 which are inclined upwardly to form an angle slightly more than 90° with side rails 13 and 14 of the member 7. The bottom members 8 and 9 have their end portions bent upwardly at the same degree of angularity, their ends being secured to the crosspieces of the end portions 11 and 12 by means such as solder.

The side members consist of inverted generally U-shaped wire pieces 15 and 16 whose lower end portions are looped around side rails 13 and 14, respectively, adjacent the end portions 11 and 12, as shown at 17 and 18, to permit swingable movement with respect to the side rails. This hinge movement of the side members 15 and 16 with respect to the bottom permits the device to be collapsed, as indicated in Fig. 3, so that a quantity of the carriers may be stacked one upon the other in a vertical relation, as shown in Fig. 4, for shipping purposes or for storage. The fact that the angle which the end portions 11 and 12 make with the side rails 13 and 14 is slightly more

than 90°, permits the interfitting of these bottoms, as shown by Fig. 4. It is apparent from this that a considerable number of carriers may be stacked within a limited space, notwithstanding the capacity of each of them to receive six bottles in the closed position, as illustrated in Figs. 1 and 2.

The rail construction of the bottom and of the side members 15 and 16 provides a carrier that has substantially no surface to which dust or dirt will cling and become a nuisance or sales deterrent.

Each side member 15 and 16 is bent inwardly, as at 19 and 21, so that a lower portion such as 22 and an upper portion such as 23, are inclined outwardly and inwardly, respectively, when the

side members 15 and 16 are moved to the closed position for the reception of bottles. Horizontal retaining members 24 and 25 of sheet metal are secured immediately below the bends 19 and 21, the end portions of the retaining members being curled around the side members 15 and 16. From this construction it is clear that when bottles 26 are set within the carrier and the side members 15 and 16 are moved to the closed position, the retaining members 24 and 25 will be tensioned against the bottles, as at 27, to hold them snugly and firmly within the carrier. The use of broad strips as retaining members 24 and 25 gives greater stability to the bottles within the carrier since they may engage the bottles at various vertical positions.

The configuration of the side members 15 and 16 permits the carrier within the closed position, to occupy a space substantially that occupied by the bottles. In this connection, it will be noted that the bottoms of the bottles, such as shown at 28, will project beyond the width of the carrier bottom, and the overall height dimension of the carrier is substantially the same as the height of the bottles 26. This permits the stacking of loaded carriers, one upon the other, and in a space substantially equal to the space that would be occupied by the bottles themselves so that the stacking space required is held to a minimum. The outer surfaces of the retaining members 24 and 25 lend themselves to effective display advertising of the contents of the carrier, so that the customer may be advised as to the merits of the drink, its trade name, generic designation, or whatever the seller deems suitable. It is apparent that loaded carriers provide a substantially unobstructed view of the bottles within, and also of the labels thereon, for more effective display purposes.

A central panel 29, in this instance of thin sheet metal, is swingably suspended by spaced upwardly projecting arms 31 and 32 from the crosspiece 33 of side member 16, the ends of the arms 31 and 32 being curled around the crosspiece. The spacing of the arms 31 and 32 permits the crosspiece 33 with the crosspiece 34 of side member 15 to form a compound handle which may be grasped for carrying. As is clear from Figure 1, the panel 29 serves as a divider for the double row of bottles to reduce the likelihood of bottle breakage through glass to glass contact, and to reduce endwise shifting of adjacent rows of bottles with respect to one another. Ears 35 are struck up from the panel 29 to divide the carrier into individual bottle compartments whereby adjacent bottles within the same row are prevented from making contact with one another, thereby reducing rattling and the breakage hazard. When the carrier is only partially filled with bottles, they will be prevented from toppling within each row because of the compartments formed by the ears 35.

A lock 36 consisting of a horizontally disposed hooked-shaped piece integral with the crosspiece 34 is provided. When the side walls 15 and 16 approach the closed position, they are tensioned from one another by the resistance imparted by retaining members 24 and 25. The lock 36 is hooked around the crosspiece 33 while under this tension to fasten the side members 15 and 16 securely together, as well as firmly hold the bottles within the carrier to prevent rattling and breakage. The lock is released by forcing the crosspieces 33 and 34 together to permit the unhooking of the lock 36.

In Figs. 5 and 6 there is illustrated a carrier suitable for the reception of a single row of bottles, more especially for larger sizes such as the twenty-four, twenty-six and thirty-two ounce bottles, the construction of this embodiment being substantially as that described above. The bottom 7' is of a narrow dimension so as to accommodate only a single row of bottles and it requires but a single member 8'. Side members 15' and 16' are similar to those already described except that they are designed to terminate at a point immediately below the bulbous portion 31' of the bottle 26'. Two lock members 38 and 39 are provided each having the configuration of lock 36 and being interspaced with respect to the bottles, as shown by Fig. 6. Each of the lock members 38 and 39 are formed integrally with the crosspiece 34' and are locked to the crosspiece 33' through the hooking arrangement already described. In this construction the side members 15' and 16' are tensioned against the bottles 26', as at 41 and 42, and, in addition, the bottles are gripped beneath the bulbous portion 31' by the crosspieces 33' and 34'. The use of spaced locks 38 and 39 assures that the bottles will be held firmly at their top portions and that there will be no toppling of the bottles in a partially filled carrier. It is clear that the carriers when filled can be stacked in a space substantially that of the bottles themselves, and when empty a number of them may be stacked in a limited space in a collapsed position after the method described. For handling purposes, the loaded carrier may be grasped by inserting the fingers between the tops of the bottles and using the crosspieces 33' and 34' as a compound handle.

Special attention is directed to a further and important advantage of my improved construction, in that it functions to materially reduce the cost of distribution of beverages of this type both as to labor and materials. In distributing the bottled beverages to retail dealers, particularly where the commodity must be moved by truck, it is necessary for the bottler to insert the bottles into wooden cases commonly holding twenty-four or twelve bottles, depending upon the size of the bottle. These cases are customarily provided with collapsible paper or cardboard separators which act to separate the bottles in the case. In this way the bottler is enabled to place case upon case in the truck, and to thus assemble a truck load within a commercially feasible space. When so arranged the cases as indicated at 43 and 44 in Fig. 7, rest upon each other at their edges, the side walls of the cases being slightly wider than the height of the bottles, and therefore the weight of the superimposed cases is taken by the box as distinguished from the bottles. It is then necessary for the bottler or distributor, upon reaching the retail establishment, to remove the bottles from the cases and place them in the carriers for delivery to the retailer. This is customarily done by the driver of the truck, and consumes a considerable amount of time in the delivery of the commodity to the retailer. Furthermore, it necessitates the use of both paper separators in the case and of carriers in the process of distribution of the commodity. It will be seen that I have constructed the carrier herein disclosed in such manner that the requisite number of carriers can be inserted into the case by the bottler and, as the bottle capping operations proceed, the bottles can be directly assembled in a single operation into both the carriers and the cases. To accomplish this,

the carriers are assembled in the cases with the locks 36 left unlatched so that the side walls 15 and 16 occupy a slightly expanded position. This permits the bottles to be freely slipped into the carriers, and therefore the carriers are latched together to confine the bottles as heretofore described. It will be seen that the overall height of the carriers is no greater than that of the bottles themselves so that the entire unit consisting of a carrier and its enclosed bottles, will rest completely within the confines of the cases so that the cases can be stacked in the same manner as though the carriers were absent.

I claim:

1. A carrier made essentially of wire for holding a plurality of narrow necked bottles such as those employing a crown cap comprising in combination a wire bottom member having a generally elongated shape and of a width substantially less than that of a pair of bottles for the use of which the carrier is intended, said bottom member having an outer frame comprising an upwardly extending end portion at each end thereof to serve as abutment members to prevent endwise displacement of the bottles, marginal wires along each side disposed beneath the bottles and at least one wire piece interconnecting the end portions intermediate said marginal wires and in the plane of the latter, a pair of side members each consisting of a pair of inverted generally U-shaped wire members only slightly greater in height than the height of the bottles and having parallel posts and an interconnecting crosspiece, the lower ends of said posts being swingably mounted to said bottom member with the said members in alignment with the elongated sides thereof, said lower ends of each of said side members being looped around said marginal wires between the end portions to be rotatable about an axis beneath and within the plane of the bottles, the posts being disposed adjacent said end portions to prevent shifting of the side members with respect to said bottom member, said side members being inclined outwardly and then inwardly above said lower ends so that said crosspieces of said U-shaped members pass over the heads of the bottles and approach each other for use as a combined handle at a height not in excess of the height of the bottles within the carriers, a metal sheet connecting the outwardly inclined portions of said posts of each of said side members to bear against and tension the bottles within the carrier when the side members are in the operative position, said sheets being located to bear along their lower edges against the sides of the bottles at their broad portions to resiliently hold the bottles together in mutual supporting relationship, and means for locking said side members in an operative position.

2. A metal carrier for a plurality of narrow necked bottles such as those employing a crown cap, the combination of a bottom member of generally elongated shape formed of a rigid material, a pair of upstanding abutment members on each end of the said bottom member for preventing endwise displacement of the bottles, a pair of side members each consisting of an inverted generally U-shaped wire member having parallel posts and an interconnecting crosspiece, the lower ends of said posts being swingably mounted to said bottom member in alignment with an elongated side thereof, the said

side members being inclined inwardly above the lower ends of said posts so that crosspieces of the said U-shaped members approach each other for use as a compound handle when the sides are in the vertical position, a panel swingably suspended from the crosspiece of one of said side members and depending to a point between the side portions of the bottles to separate two parallel rows of bottles to reduce the tendency of endwise shifting of each of the rows of bottles with respect to one another, means projecting outwardly from said crosspiece at substantially a right angle with respect thereto to provide individual compartments for each bottle within each row, means running horizontally between the legs of each side members for supporting and exerting tension upon the bottles and the carrier, said means being located to bear against the sides of the bottles at their broad base portions to hold the bottles together in mutual supporting relationship, and means for locking the said side members in an operative position.

3. In a carrier for holding a plurality of narrow necked bottles such as those employing a crown cap, the combination of a bottom member having a generally elongated shape and of a width substantially less than a pair of bottles for whose use the carrier is intended, said bottom member comprising an outer frame formed of an endless wire piece having an upwardly projecting end portion at each end to serve as abutment members to prevent endwise displacement of the bottles and having at least one wire piece interconnecting the end portions of the said outer frame to support the bottoms of the said bottles, a pair of side members each consisting of a pair of inverted generally U-shaped members having parallel posts and an interconnecting crosspiece, the lower ends of said posts being swingably mounted to said bottom member in alignment with an elongated side thereof, said lower ends of each of said side members being looped around the said outer frame between the said end portions thereof and proximate to the end portions to prevent shifting of the side members with respect to the said outer frame, the said side members being inclined outwardly and then inwardly above the said lower ends so that the crosspieces of the said U-shaped members approach each other for use as a compound handle at a height not in excess of the height of the bottles within the carriers, a metal sheet connecting the outwardly inclined portions of the posts of each of said side members for tensioning the bottles within the carrier when the side members are in the operative position, said sheets being located to bear along their lower edges against the sides of the bottles at their broad portions to resiliently hold the bottles together in mutual supporting relationship, means for locking the said side members in an operative position, a metal panel having spaced upwardly projecting arms swingably suspended from a crosspiece of one of said side members and depending to a point between the wide portions of the bottles, and outwardly projecting ears struck from said panel and disposed at right angles thereto in the area between the wide portions of the bottles to separate the bottles and to prevent shifting of the bottles with respect to one another during handling.
